(57) **CLAIM**

I claim the ornamental design for a snowman wreath hanger, as shown and described.

DESCRIPTION

FIG. 1 is a perspective view of a snowman wreath hanger showing my new design;

FIG. 2 is a front view thereof;

FIG. 3 is a rear view thereof;

FIG. 4 is a top view thereof;

FIG. 5 is a bottom view thereof;

FIG. 6 is a left side view thereof;

FIG. 7 is a right side view thereof; and,

FIG. 8 is another perspective view thereof shown in a used condition with a wreath shown in broken lines.

The broken lines depict environmental subject matter only and form no part of the claimed design.
